FLUSH TYPE LATCH OPERATOR

Earl B. Young, Pueblo, Colo.

Application June 23, 1938, Serial No. 215,471

4 Claims. (Cl. 292—167)

This invention relates to an improved operating means for closures, particularly aeroplane and motor vehicle doors.

It is a particular object of this invention to provide a latch operator for aeroplane or automobile doors to eliminate the outside door handle to thereby add to the beauty of the vehicle, and to provide, in lieu of the conventional outside handle, flaps normally positioned to lie flush with the outer side of the door and adapted to be pressed inwardly to retract the door latch.

Still a further object of the invention is to provide a handle mounted on the inner side of the door for opening the door from within, and for actuating means to engage the afore-mentioned flaps to hold them from being pressed inwardly to lock the door to prevent it from being opened from the outside.

A salient advantage of this invention resides in the elimination of the outwardly extending outside handles which may be accomplished through the use of this operator; the simplicity of construction and operation thereof; and the simple yet efficient means whereby the door may be locked to prevent opening from the outside.

Other objects and advantages of the invention will hereinafter become more fully apparent from the following description of the drawings, which illustrate a preferred form of the invention, and wherein—

Figure 1 is a side elevational view, partly in section, of the mechanism comprising the invention, as seen from the inside of the door.

Figure 2 is a top plan view of the same.

Figure 3 is a view similar to Figure 1 showing the latch bolt in section and the remaining parts of the invention in elevation.

Figures 4 and 5 are horizontal sectional views taken on the lines 4—4 and 5—5 respectively, of Figure 1, and

Figure 6 is a vertical sectional view taken on the line 6—6 of Figure 1.

Referring more particularly to the drawings, wherein like reference characters indicate like or corresponding parts throughout the different views, 10 designates the outer wall of a vehicle door, of conventional construction, which is provided with an inner wall 11 and the end walls 12 which are secured together by the removable fastenings 13 to form the interior space or housing 14. The parts heretofore described are of conventional construction, being shown merely to illustrate the application of the invention to an automobile door, and it is to be understood that the invention is likewise adapted for use

with various other forms of swinging closures, particularly aeroplane doors.

Secured to the inner side of the outer wall 10 adjacent the free end of the door, is a housing 15 in which is slidably mounted a latch bolt 16 having a hollow interior 17 and a restricted opening 18 at its inner end. A rod 19 is provided with an enlarged head 20 at one end, which is mounted in space 17 and held against the inner end thereof by an expansion 10 coil spring 21, as best seen in Figure 3.

Beneath the latch bolt 16, the outer wall 10 is provided with a pair of spaced openings in which are positioned the flaps 22 and 23, which are preferably formed by cutting out portions 15 of the wall 10 so that the flaps 22 and 23 will correspond in appearance to the outer side of the door. The adjacent portions of the flaps 22 and 23 are secured on their inner sides to the rods 24 and 25 at 26, these rods being journaled in the bearing members 27 secured to the inner side of the wall 10. The opposite ends of the rods 24 and 25 are provided with the cranks 28 and 29 which are disposed at oblique angles to flaps 22 and 23, respectively, and which project in opposite directions relatively to each other when the flaps are in a closed position as seen in Figures 1 and 4. Cranks 28 and 29 are provided with the inwardly extending lugs 30 to be engaged by one end of the coil springs 31 30 which are mounted on the rods 24 and 25 to hold cranks 28 and 29 against the wall 10 to thereby normally retain flaps 22 and 23 in the openings in the door, so that they will lie flush with the outer side of the door as best seen 35 in Figure 5. Flaps 22 and 23 may be provided with the inwardly and outwardly extending offset lugs 32 to prevent them from moving beyond a flush position in the outer wall 10 of the door. Rods 33 and 34 are pivotally connected at their 40 corresponding ends by means of the bolts 35, to the cranks 28 and 29 respectively. As best seen in Figures 1 and 4, the corresponding free ends of the rods 19, 33 and 34 are provided with the enlarged concave portion 36. Caps 37, which 45 are provided with the restricted opening 38 at one end, are slidably mounted on the free ends of these rods and provided with the openings 39 adjacent their opposite rounded closed ends 40. Expansion coil springs 41 are mounted on 50 these rods, with their opposite ends in engagement with the restricted ends 38 and with the portion 36 to urge said portion toward the ends 40.

A lever 42 is pivotally mounted intermediate of its ends at 43, and is provided with the balls 55

44 and 45 which are spaced at equal distances from the pivot 43, and the ball 46 at the upper end of the lever 42. The ball 44 is adapted to be connected to the rod 33, ball 45 to rod 34, and 5 the ball 46 to the rod 19. This connection is made by pulling outwardly on the caps 37 to retract the end 36 so that the balls may be inserted through the openings 39, after which the caps 37 are released causing the springs 41 10 to draw the caps 37 inwardly on the rods so that the balls are held between the ends 40 and the portion 36 to thereby form the universal ball and socket joint.

A handle 47 is positioned on the inner side of 15 the door, and is provided with a shank 48 disposed substantially at right angles thereto, which is journaled in a boss 49 in the inner wall 11, and which is provided at its free end with a crank 50 connected by the pin 51 to a hook 20 52 which extends forwardly with its bill 53 turned downwardly to engage an upwardly extending lug 54 on the inner end of the latch bolt 16, to retract the latch bolt when the handle 47 is swung downwardly to swing the crank 25 50 upwardly and rearwardly. Hook 52 is held in engagement with the lug 54 by means of a bracket 55, secured to the inner side of the wall 10 and engaging the top side of the shank to prevent it from lifting upwardly at its forward 30 end when drawn rearwardly by the operation of the handle 47.

The yoke shaped member 56, having corresponding downwardly extending ends 57 and the enlarged upwardly extending intermediate portion 58, provided with the slot 59, is slidably mounted on the inner side of wall 10 by means of the brackets 60 in which ends 57 are slidably mounted, and by means of the pin 61 which engages the slot 59. Springs 62, which are secured 40 at their corresponding ends 63 to the wall 10, and which are coiled intermediate of their ends, have their opposite free ends engaging the ends 57 of the yoke 56 to normally retain it in a raised position with the upper edge of the enlarged portion 58 in engagement with the shank of the hook 52. By swinging the handle 47 upwardly from its normal position, crank 50 and the shank of the hook 52 will be swung downwardly to force the yoke 56 downwardly against the action 45 of the springs 62 to move the ends 57 of the yoke, into an overlapping engaging position relatively to the flaps 22 and 23, as seen in Figure 3, to prevent the flaps from being opened or pressed inwardly to retract latch bolt 16.

55 From the foregoing it will be seen, that flaps 22 and 23 can be pressed inwardly from without to swing their cranks 28 and 29 respectively through an arc toward each other to cause the upper end of lever 42 to be moved away from the housing 15 to retract the latch bolt 16 to open the door. When the inward pressure on the flaps 22 and 23 is released, the springs 31 will force the cranks 28 and 29 away from each other to return the flaps to their normal position in the wall 60 65 thereby permitting the latch bolt 16 to be returned to its normal projected position. Latch bolt 16 may be retracted from the inside by a downward pressure on the handle 47, as heretofore described, and the spring 21 is provided so 70 that when the latch bolt 16 is operated by the handle 47 it may move relatively to the rod 19 without actuating the flaps 22 and 23 and when handle 47 is returned to its normal position spring 21 bearing against the head 29 will return latch bolt 16 to its projected position. An 75

upward movement on the handle 47, from its normal position, as heretofore described, will project the yoke 56 downwardly causing its ends 57 to move into engagement with the inner sides of the flaps 22 and 23 thereby locking the door 5 to prevent it from being opened from the outside.

Various modifications and changes in the particular construction of the parts and in their arrangement may obviously be made and are 10 contemplated, and the right is reserved to make such variations and changes as do not depart from the spirit and scope of the invention as hereinafter defined by the appended claims.

I claim as my invention:

1. A device of the class described comprising a pair of spaced flaps adapted to be mounted in spaced openings in the outer wall of a door to normally lie flush with the outer side thereof, rods journaled on the inner side of said wall 20 and secured to the adjacent portions of said flaps to pivotally mount them, cranks formed on opposite ends of said rods and provided with springs to normally hold said flaps in a closed position flush with the outer side of said door, 25 a lever pivotally mounted intermediate of its ends, links pivotally connecting said cranks to said lever on opposite sides of its pivot, and one end of said lever being adapted to be connected to a sliding door latch bolt to retract the latch 30 bolt when said flaps are pressed inwardly.

2. A latch operator and locking device for doors comprising operating members pivotally mounted on the inner side of the outer wall of a door and disposed in openings therein, spring means to normally retain the operating members in the openings, a lever pivotally connected intermediate of its ends, rods connected to said operating members and to said lever on opposite sides of its pivot point, a latch bolt having a hollow shank provided with a restricted opening in one end, a rod having an enlarged end mounted in said shank, an expansion spring normally retaining said end in engagement with the restricted end of said shank, said rod being connected at its opposite end to one end of said lever for retracting said latch bolt when said operating members are pressed inwardly; a handle journaled on the inner side of said door, 40 outwardly extending ear, a hook pivotally connected to said ear and engaging said latch bolt for retracting the bolt against the action of its coil spring when said handle is swung downwardly; and a yoke slidably mounted on the inner side of said wall and provided with spring means to normally hold it in a retracted position, said yoke being projected by engagement with said hook when the handle is swung upwardly, to move the free ends of the yoke into overlapping relationship to said operating members to retain them in a closed position.

3. In a latch operator for swinging closures, flap members adapted to be pivotally mounted on the inner side of the outer wall of a closure, said wall having spaced openings, spring means normally retaining said flaps in said openings, a lever pivotally mounted intermediate of its ends, links connecting said flaps to said lever on opposite sides of its pivot, and a rod connected to one end of said lever and to a sliding latch bolt for retracting the bolt by an inward movement of the flap members.

4. A latch for swinging closures comprising a latch bolt having a hollow shank provided with

15

35

40

45

50

55

60

65

5 a restricted opening in one end thereof, a rod having one end extending through said opening and provided with an enlarged head disposed in said hollow shank, expansion spring means mounted in said shank and normally holding said rod in an extended position, a lever pivotally mounted intermediate of its ends on the inner side of said closure and pivotally connected at one end to the opposite end of said rod, said 10 closure being provided with an opening, an operating member, spring means normally retaining the operating member in said opening, link means connecting said operator to the opposite end of said lever, said operating member being movable inwardly to actuate said lever to retract the 15 latch bolt; a handle disposed on the inner side

of said closure and having a shank journaled therein and provided with a crank, a hook pivotally connected to said crank and having its bill engaging said latch bolt for retracting it when said handle is swung downwardly, said latch being movable thereby relatively to said rod to contract said spring whereby the bolt is projected when the handle is released, locking means slidably mounted relatively to the closure and operated by the upward movement of said handle to lock the operating member in an inoperative position, and spring means normally urging said locking means out of engagement with the operating member.
